UNITED STATES PATENT OFFICE.

CLINTON E. LARRABEE, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK.

ELIMINATION DEVICE FOR TIME-RECORDERS.

1,277,086.

Specification of Letters Patent. Patented Aug. 27, 1918.

Application filed August 21, 1916. Serial No. 115,980.

To all whom it may concern:

Be it known that I, CLINTON E. LARRABEE, residing at Binghamton, county of Broome, and State of New York, have invented certain new and useful Improvements in Elimination Devices for Time-Recorders, of which the following is a full, clear, and exact description.

This invention relates to certain new and useful improvements in elimination or throw out devices for cost keeping time recorders.

In keeping costs with time recorders, it had been found desirable to divide the working hours of the day into a number of units and to disregard the time when the shop is not working. In this way, the clerical work connected with cost keeping is simplified. Consider for example a man starting to work at 8 o'clock and working until noon, then having an hour off for lunch and in the afternoon working one hour. The old forms of cost keepers would show on the card "In" 8.00, "Out" 12.00, "In" 1.00, "Out" 2.00. With the present embodiment, the card would merely show 0.00—050 or a total of 5 hours work performed. The advantages of such an arrangement will be obvious.

It will be understood that in order to have the type wheels print such a record it is necessary to provide a means for disabling or disconnecting the type wheels from the clock driving mechanism during the non-working periods. With a 24-hour calendar day with four non-working periods of one hour each, the hour wheel would have 20 characters thereon and would be disconnected from the driving clock four times a day for periods of one hour each.

The present invention resides in the provision of a simple mechanical mechanism for disconnecting the clock mechanism from the type wheels at predetermined time periods during the day. Other objects of the invention will be set forth in the accompanying specification and in the accompanying claims.

In the drawings:—

Figure 1 shows a front view of a time recorder showing my invention embodied therein. The inclosing casing is removed to show the interior construction.

Fig. 2 is a side elevation of the recorder shown in Fig. 1.

Fig. 3 is a top detail view of the elimination or cut out devices for the recorder type wheels.

Fig. 4 is a side detail view of the parts shown in Fig. 3.

Fig. 5 is a detail view of the cam devices which operate the throw out mechanism shown in detail in Figs. 3 and 4.

Fig. 6 is a central sectional view of the parts shown in Fig. 4.

Fig. 7 is a central sectional view of the type wheels showing the driving connection between the units wheel and the drive shaft connecting to the throw out devices.

Fig. 8 is an illustration of a card with time impressions thereon, and showing the operation of the recorder.

In more detail in the drawing the frame 10 of the machine carries the usual and well known time recorder parts, namely impression plates 11, handle 12, carbon ribbon 13 fed forwardly by the operation of the handle 12. To print upon the card the card shown in Fig. 8 is placed in the chute M and the handle 12 is pressed down. Impression plate 11 is first swung downward and then its operating spring swings it upwardly striking the lower face of the card and taking an impression of the positioned type wheels which are above the carbon ribbon 13. The type wheels are preferably three in number, namely, 14, 15, 16. 14 is the minutes or units wheel and is driven by means of gears 17 and 18 from a drive shaft 19. The hour wheel 15 preferably having 20 characters thereon is advanced once each revolution of the minutes or units wheel by suitable transfer devices T. These devices also are adapted to advance the day wheel 16, once each revolution of the hour wheel. Just before the impression platen operates, the units wheel 15 is aligned and locked by means of a pawl 20 which cooperates with notches in an alining disk 21, secured to the units wheel as shown in Fig. 7. The pawl 20 is operated through a rock shaft 22 which is oscillated by an operating rod 22a which in turn is operated from the impression platen operating means as shown in Fig. 2. The driving shaft 19 extends up to a clutch de-

vice which is adapted to clutch and declutch the said shaft from a clock driven shaft 23 as will now be described.

Clutch.

5 The clock driven shaft carries at its lower end a boss 24 which has secured thereto a disk 25 having a plurality of spaced holes 26 therein as shown in Figs. 3 and 6. Type wheel driving shaft 19 is axially aligned with shaft 23 and extends up through disk 25 and boss 24 and is freely rotatable with respect thereto. A clutch disk 27 is free to slide vertically upon a sleeve 28 which is 10 pinned to the shaft 19. This clutch disk carries two clutch pins 29. One of these clutch pins passes through a hole in a bent plate 30 which plate is securely fastened to the upper end of the sleeve 28. The plate 30 causes a rotation of shaft 19 upon the rotation of clutch disk 27 and allows a vertical movement of the said disk. Below the clutch disk is a stationary plate 31 having a series of circumferentially spaced holes 32 therein. 15

20 In order to shift the clutch disk vertically I provide shifter arms 33 which are secured to a rock shaft 35. These shifter arms having notches at their edges to receive the edge of the clutch disk. When the clutch disk is 25 in raised position as shown in Fig. 6, the clutch pins 29 pass into the holes 26 in disk 25 and with this position of parts the shaft 19 is driven in unison with clock shaft 23. When the clutch disk is in lower position 30 (see Fig. 4) the clock driven shaft 23 and type wheel driving shaft 19 are disconnected from each other. The type wheel driving shaft is also locked against movement as the lower ends of the clutch pins 35 have entered the holes 32 in the stationary plate. 40

Clutch operating mechanism.

Clock driven shaft 23 through gears 37 and 38, shaft 39 and pinion 40, drives an 45 elimination wheel 41. The gearing is such that the elimination wheel makes one complete revolution every twenty-four hours. The elimination wheel has a circumferential slot 50 in its face and this slot is adapted to receive tripping devices 42. In Fig. 1 two of these tripping devices are positioned at noon and one o'clock and others are positioned adjacent the evening "off" position. 55 Pivoted adjacent the elimination wheel is an elimination lever 43 which carries a tooth adapted to be engaged by the trip devices. Referring to Fig. 1 it will be seen that the elimination lever is lifted at 12 60 o'clock and then allowed to drop only to be again raised and lowered at one o'clock. The opposite end of the elimination lever through part 43^a and pin 44 connects with a counterweighted rock lever 45 pivoted on shaft 46. Freely rotatable on this shaft is 65

a ratchet member 47 which has secured thereto a cam member 48. Rock lever 45 has pivoted thereon a spring pressed feed pawl 49 which engages the teeth of ratchet 47 as shown in Fig. 5. The ratchet wheel 70 47 is fed forward one step each time the elimination lever descends after being raised by the trip device on the elimination wheel, a counterweighted retaining pawl 50 preventing a retrograde movement of the 75 ratchet wheel. Rigidly secured to rock shaft 35 which carries the clutch shifting arms 33 is a follower pawl 51 which rests against the cam 48. The pawl follower is held against the cam by a counterweight 52 and the weight of this counterweight is sufficient to elevate the shifter arms when the follower drops into the depressions in the cam. 80

The operation of the device will be readily understood. There are one-half as many depressions on cam 48 as there are teeth on ratchet 47, consequently the follower will be held upon the high part of the cam during the entire period beginning with the 90 elevation of the elimination lever by the first trip device (positioned at 12 o'clock) and ending after the elimination lever has dropped after passing the second trip device (positioned at 1 o'clock). During this 95 entire period the cam disk will be held down in the position shown in Figs. 4 and 5 and since the clutch pins are out of the holes 26 in disk 25 the clock driven shaft 23 and type wheel driving shaft will be disconnected. During this period the type wheels 100 will be locked in the manner previously explained.

At all other times the follower 51 will 105 rest in the depressions in the cam 48 and the clutch disk will be elevated by counterweight 52. With this condition of parts the clutch pins have passed into the holes in disk 25 thereby connecting the clock shaft 19 and type wheel driving shaft 23. 110

The construction herein described is particularly advantageous in recorders in which the decimal system is used for the minute type wheels. These wheels preferably carry ten characters thereby simplifying the subtractions and computations made from the record card. When a throw out occurs the parts are so timed that one of the pins enters one of the holes in the locking plate thereby holding the minute or decimal wheel at the exact point to which it had been advanced by the clock mechanism. On account of the varying positions of the clock driven disk it is necessary that the clutch disk 27 and pins 29 should not be positively forced into upper position as the holes might not be in exact alinement with the pins. The counterweight arrangement obviates the use of a positive clutch lifting device and permits the clutch pins to register in the holes 120 125 130

in the disk 25 when the clock has advanced the disk into such a position that the holes 26 register with the pins. For ordinary purposes it has been found that 10 divisions on the minute wheel and ten holes are satisfactory but it is to be understood that any number of divisions and holes may be employed depending upon the degree of accuracy desired upon the record card.

10 My invention is susceptible to various modifications, as will occur to those skilled in the art, and it is to be understood that my invention is not limited to the precise form shown and described. What I claim as my 15 invention is particularly set forth in the appended claims.

I claim:

1. In a time recorder, in combination with type wheels, driving means therefor, and 20 a clock driven element, of clutch members connected to said clock-driven element and said driving means respectively, one of said clutch members being weight-pressed to move in a direction to engage the other, 25 means for positively moving said movable clutch member, against the stress of its weight, in a direction to disengage from its fellow member at the beginning of a non-working period, and means whereby said 30 weight-pressed clutch member, when released from the control of said positive actuating means, is restrained from reengaging its fellow member until the clock-driven element has moved to the succeeding digit position.

2. In a time recorder, in combination with type wheels, driving devices therefor and a 35 clock driven element, means for coupling and uncoupling the clock driven element and 40 the driving devices, said means comprising a rotatable element moving in unison with

the clock driven element and having a series of apertures therein, a clutch element rotatable in unison with the driven element, clutch pins carried thereby and adapted to 45 engage the holes in the first mentioned rotatable element, to couple the driving device and the clock driven element together, a stationary plate having holes therein below the clutch element the said holes being 50 adapted to receive the clutch pins and maintain the driving devices stationary when they are uncoupled from the clock driven element, and a clutch shifting means operating at predetermined time intervals for 55 shifting the said clutch element.

3. In a time recorder, in combination with type wheels, driving devices therefor, and a clock driven element, of means for coupling and uncoupling the clock driven element and 60 the driving devices, said means comprising clutching elements associated with the driving devices and complementary devices associated with the clock driven element, means for operating the clutching elements, 65 said means comprising a ratchet and a cam associated therewith, a cam follower operatively connected with the clutching elements and a counterweight to move the same in one direction, a pivoted lever to advance the 70 said ratchet wheel and a clock driven elimination wheel having provisions thereon for rocking the pivoted lever at certain set time periods.

In testimony whereof I hereunto affix my 75 signature in the presence of two subscribing witnesses.

CLINTON E. LARRABEE.
